(57) **CLAIM**

The ornamental design for a band saw machine, as shown and described.

DESCRIPTION

FIG. 1 is a perspective view of a band saw machine;

FIG. 2 is a front view thereof;

FIG. 3 is a rear view thereof;

FIG. 4 is a top plan view thereof;

FIG. 5 is a right side view thereof; and,

FIG. 6 is a left side view thereof.

The broken line showing of the band saw machine is included for the purpose of illustrating portions of the band saw machine and forms no part of the claimed design.
